[57] CLAIM

The ornamental design for a pen-like dispenser, as shown and described.

DESCRIPTION

FIG. 1 is a front perspective view of a pen-like dispenser showing our new design;

FIG. 2 is a reduced front elevational view;

FIG. 3 is a reduced left side elevational view, the right side being a mirror image thereof;

FIG. 4 is a reduced rear elevational view;

FIG. 5 is an enlarged top plan view;

FIG. 6 is an enlarged bottom plan view; and

FIG. 7 is a front elevational view showing the dispenser of FIG. 1 in an exploded condition.

FIG. 1
